JOSEPH LEDWINKA, OF PHILADELPHIA, PENNSYLVANIA, ASSIGNOR TO EDWARD G. BUDD MANUFACTURING CO., OF PHILADELPHIA, PENNSYLVANIA, A CORPORATION OF PENNSYLVANIA

PRESSED METAL AUTOMOBILE BODY

Application filed September 1, 1927. Serial No. 216,801.

This invention relates to an automobile body construction of the "composite" type.

It has been customary to construct "composite" automobile bodies by first forming the wooden frame to correspond to the contour of the body desired, and then securing over such frame separate panel strips, which serve merely as a covering for giving the body its finished external appearance. These panel strips do not coat materially with the frame for strengthening the body. The accurate dimensions of the door openings of the body must be obtained by finely fitting and cutting the frame members. This naturally entails additional time and cost of production, and often results, as well, in inaccurate fits between the doors and their frame. Of course, the same difficulty arises likewise in connection with the window and windshield openings where laterally movable closure members are used. Further disadvantages occur in the use of separate panel strips since they cannot be formed in a single die stamping operation, applied quickly as one unit, and materially increase the number of exterior joints throughout the body.

The principal object of the present invention is to provide a "composite" body construction, wherein the fit between the doors and other laterally movable closure members and their openings or frames will be accurate and its obtainance not dependent upon precise cutting and interfitting of the wooden frame elements.

Another important object is to provide such a construction wherein the paneling or sheathing enters into the body as an integral structural part, serving mutually with the frame to effect the requisite strength against the stresses and strains of usage.

There are additionally other objects, among which are the reduction in number of the exterior joints and structural parts, together with reduced cost and time of production and assembly.

Of course, even further objects and advantages will become apparent during the detailed description of the invention to follow.

In accomplishing these objects it is pro-

posed to utilize a one-piece stamping of sheet metal to form the outer side paneling of the body and to arrange such stamping upon a main wooden frame. The stamping would be formed with a deep draw, of substantially the full depth of the side of the body, the corners of the door openings being rounded with generous curves so that the door jamb could be made at one die stamping operation. In view of the deep draw of the stamping, it is contemplated that the wooden framework could fit substantially within the outer paneling. In this way the contour and dimensions of the door and other openings for the laterally movable closure members, such as windows, windshields, would be established by the paneling, which being formed by die stamping in a single operation would be accurate and constant. Following as a concomitant, the wooden framework may be formed so as to merely substantially approximate the dimensions and contour of the door and other openings. The paneling may be tacked, screwed or otherwise secured to the frame.

An embodiment of the invention is illustrated in the accompanying drawings wherein—

Figure 1 is a side elevational view of the door frame portion of a composite body constructed in accordance with the invention, the wooden frame members and the forward door being indicated by the dot and dash lines.

Figure 2 is a horizontal sectional view taken on line 2—2 of Fig. 1, the door being omitted.

Figure 3 is a vertical sectional view taken on line 3—3 of Fig. 1, and

Figure 4 is a vertical sectional view taken on line 4—4 of Fig. 1.

The embodiment illustrated in the drawings is directed to a body of the sedan type, but it is understood that the invention is also applicable to coupes and other types of bodies. Also, there has been shown only that part of one side of the body extending from the cowl to the rear post of the rear door, it being well understood that the tonneau portion or a part thereof could be included in the one

piece panel and that the invention embraces as well the completed body.

The entire side paneling of the body, or as shown, that portion of the body paneling extending from and including the cowl to the rear post of the rear door, is formed by a one-piece continuous sheet metal stamping 1. This stamping extends all the way around the door openings 2 and 3 thereby forming continuous frames therefor. The part of the stamping, which forms in effect the A post of the body, has its outer side formed into the desired curve or shape as at 4, one end of such side terminating in the rearwardly projecting flange 5 serving as a seat for the windshield, while the other end is configured to form the door jamb. This latter end is substantially an inwardly extending flange of double Z configuration, the part 6 of which forms the door jamb proper, the flange 7 the inner door stop, and the angle 8 a rabbet for the door overlap.

The stamping at the B-C or intermediate post forms substantially an inwardly presenting channel having a base 9 and side walls 10 and 11 of double Z formation corresponding to the similar part of the A post and serving the same purpose.

The part 12 of the stamping contiguous to the D or rear door post is in the form of a double Z, the innermost Z of which serves as a door jamb, while the outermost Z is secured to the frame and forms a seat for the joinder of the tonneau paneling thereto. The tonneau paneling 13 may have its forward edge inwardly and forwardly flanged at 14 so as to nest in that portion of the side paneling forming the rear door rabbet.

Across the upper part of the door openings 10 the paneling 1 is formed with a door jamb portion 15 of the same configuration as the corresponding portions of the posts. The paneling along the top of the body is also shown as having an angle portion formed by the arms 16 and 17, within which the wooden frame member 18 may nest. There may be other forms wherein the arm 17 would extend upwardly and form the curved quarter portion of the roof.

At the threshold the stamping is in the form of an inwardly presenting channel, the outer wall 19 of which has an inwardly offset portion 20 forming a rabbet for the lower edge of the door. The bottom wall 21 of the channel may extend under the body sill while the upper wall 2 is upwardly and inwardly inclined to correspond with the remainder of the door jamb.

The detailed configuration of the stamping having been described, the remainder of the description will deal with the formation of the stamping and frame in more general terms. It might perhaps be opportune to state here, that the drawings are more or less a diagrammatic showing and that various

other specific configurations might be imparted to the stamping and to the panel, and that the stamping could be formed to extend a part or all of the way around the tonneau.

As previously stated, the paneling is formed from one piece of sheet metal by a single die stamping operation. The stamping operation effects a deep drawing of the sheet so that the depth of the post, threshold header and other portions of the paneling about the openings for the laterally movable closures are substantially equal to the depth of the body wall. In order that the complete panel may be formed at one operation, the corners of the openings are rounded on generous curves. It is understood, of course, that the panel is given the desired vertical and longitudinal curvature.

The framework may be formed in any well known manner and may comprise the usual sill members 23, vertical post members 24, and header members 18. The sill members may be straight and the longitudinal curvature of the body furnished by the paneling, but since the posts and headers are substantially of the same depth as the paneling, these members must approximate the vertical curvature of the body. However, since the door jambs are formed exclusive by the paneling there does not have to be accurate fitting and sizing of the posts or headers. If desired, the B-C or intermediate post may be eliminated since the paneling forms a channel not requiring any additional element for the post. A cover panel 25 may be secured under the door stop flanges of the post, and forms therewith a box girder construction for further strengthening the same.

The paneling, of course, when placed over the framework fits around and about the frame members and is secured thereto in any suitable manner. Molding strips may be used wherever it is necessary to cover up and conceal open joints or seams. Likewise where a "kick-up" is to be provided for the rear wheel housing, the frame and panel may be formed so as to furnish the shape desired.

The foregoing description has shown that provision is made for obtaining accurate fits between the laterally movable closures of the body and their jambs or frames not requiring the difficult precision in cutting and fitting the wooden frame members usually necessary in composite bodies. This provision is brought about by the employment of the one piece stamping having openings the edges of which define the limits of the jambs for the said closures independently of the frame. The use of the one piece stamping reduces the number of production operations since the same is die stamped in one operation. Naturally the cost and time of production is similarly reduced. The one piece stamping serves not simply as a cover for the frame but actually enters into the body structure as

a structural and necessary element thereof, serving together with the frame to impart the requisite strength to the body to withstand the stresses and strains of usage. Further, the use of the construction allows the wooden frame members to be formed of cheaper stock, since the entire body strength is not dependent thereon. The paneling being of one piece the number of exterior joints usually found in composite bodies is reduced with a resulting economy in eliminating the need for puttying or other filling operations.

The following claims are added with the understanding that the invention is susceptible of various modifications and adaptations within the scope thereof.

What I claim as new and useful is:

1. An automobile body construction comprising a main wooden frame including vertical and longitudinal members and a one-piece sheet metal panel applied and secured to said frame, said panel being provided with a closure opening within its margins and flanged inwardly in the margin of said opening to provide a continuous closure frame including the jamb face of said opening for a laterally movable closure member and defining the limits of the closure opening independently of the main frame.
2. An automobile body construction comprising, in combination, a wooden frame and a one-piece panel secured to said frame and extending from the forward edge of the cowl to the rear of the rear door, said panel forming continuous front and rear door frames of a depth substantially equal to the thickness of the body wall and defining the limits of the door openings independently of the wooden frame.
3. An automobile body construction comprising, in combination, a wooden frame having longitudinal and vertical members, and a one-piece continuous sheet metal side panel completely embracing said frame, said panel having a door opening therein the peripheral edges of which are formed by inwardly extending flanges forming the door jamb independently of the wooden frame and of a depth equal to the full depth of the wall of the body.

4. An automobile body construction comprising, in combination, a one-piece continuous sheet metal side panel having a door opening therein, and a wooden frame having longitudinal and vertical members, said panel having its exterior peripheral edges flanged around and secured to said vertical and longitudinal frame members and the peripheral edges of said door opening inwardly flanged to a depth equal to the full depth of the wall of the body to form the door jamb, whereby the dimensions of the door openings are accurately established by the said panel and an accurate fit between it and the door may be attained.

5. An automobile body construction comprising in combination, a wooden frame having longitudinal and vertical members, and a one-piece sheet metal panel applied to said frame and secured thereto, said panel having a door opening within its margins and being provided in said opening with continuous inwardly extending flanges framing the opening, said flanges serving as the door jamb and solely establishing the fit between the door and the opening, whereby accurate fitting and sizing of the wooden frame is eliminated.

In testimony whereof he hereunto affixes his signature.
